United States Patent Office

Des. 187,268
Patented Feb. 23, 1960

187,268

COFFIN

Alexander J. Duke, Los Angeles, Calif., assignor to
Maurice H. Kraines, Compton, Calif.

Application March 30, 1959, Serial No. 55,236

Term of patent 14 years

(Cl. D19—1)

FIG. 1.

FIG. 2.

FIG. 3.

FIG. 4.

FIG. 5.

FIG. 6.

Fig. 1 is a perspective view of a coffin showing my new design;

Fig. 2 is a top plan view;

Fig. 3 is a side, elevational view, the opposite side being substantially a mirror image thereof;

Fig. 4 is a bottom plan view;

Fig. 5 is an end elevational view, the opposite end being substantially a mirror image thereof; and

Fig. 6 is a fragmentary, cross-sectional view thereof, to an enlarged scale, taken on the broken line 6—6 of Fig. 3.

I claim:

The ornamental design for a coffin, as shown and described.
